UNITED STATES PATENT OFFICE.

THEODORE C. ADAMS, OF PORTLAND, OREGON.

SPRAY-BRUSH.

1,120,659.

Specification of Letters Patent. Patented Dec. 15, 1914.

Application filed January 12, 1914. Serial No. 811,508.

To all whom it may concern:

Be it known that I, THEODORE C. ADAMS, a citizen of the United States, residing at Portland, in the county of Multnomah and 5 State of Oregon, have invented certain new and useful Improvements in Spray-Brushes, of which the following is a specification.

My present invention relates to spray brushes and has for its object to provide a 10 brush equipped with a fountain and means for supplying the contents thereof to the bristles of the brush.

An embodiment of my invention in a tooth brush is seen in the accompanying 15 drawing, in which,

Figure 1 is a back side or plan view of the complete device as equipped for use. Fig. 2 is a side elevation of same, partly in section, showing the structural arrangement and 20 the manner of securing the members together. Fig. 3 is an elevational view of a stopper.

Referring to the drawing by numerals, 1 designates the usual back member of a 25 brush of the form employed for brushing the teeth. In this case the stem is formed at a slight angle with reference to the portion carrying the bristles; and a longitudinal aperture 2 is formed from the ex- 30 tremity of the handle portion which leads to the front side thereof, opening at an angle with reference to said front face among the bristles secured thereon. At the terminal of the handle is formed a shank 4, 35 which is screw threaded at 4^b for a portion of its length to engage the corresponding screw threads in the aperture formed in the front end of the elliptical handle frame 3. This frame is formed of a strip of metal of 40 a size and shape to be conveniently carried in the hand, the inner faces of the frame being concave to form a seat adapted to receive the flexible bulb 6, whose body is made to conform to the seat and of a size to fit 45 snugly therein. At the forward end of the frame is a recessed portion 5 adapted to receive the flanged neck 6^a of the bulb 6. The shank 4 is reduced beyond the screw threaded portion as at 7 and rounded at its 50 end so as to readily be inserted into the mouth of the bulb. This terminal portion fits snugly in the neck 6^a pressing it tight against the shouldered portion 5 of the frame and thereby prevents leakage from 55 the bulb. The ordinary rubber bulb may

be collapsed and pressed into place in the frame, when it will expand to fit neatly therein. The fountain may be filled by removing the brush and compressing the sides of the bulb to expel the air. Then upon in- 60 verting the bulb with its mouth in the liquid used and releasing it, the walls of the bulb will expand which will cause the liquid to be drawn into the bulb, in the well known manner. I prefer to form the frame 3 of 65 metal, but it may be made of celluloid, or other suitable material. The brush may be removed for packing when the bulb may be closed by means of a cork 8 which is pro- 70 vided with a shank having a screw threaded 75 portion 4^b, and an entering terminal 7^b. In use, the contents of the bulb may be forced through the aperture 2, by a slight pressure upon the bulb 6, when the liquid will issue through the bristles in a spray, as 75 the user is brushing the teeth, so that the material may be applied as wanted. By means of the frame 3 the brush may be manipulated at will without affecting the bulb; and the location of the latter is such 80 that it may be operated by the fingers of the same hand.

What I claim as new, is—

A fountain brush comprising a brush proper having a stem provided with a lon- 85 gitudinal aperture opening in the face of the brush, a shank formed at the terminal of said stem, provided with screw threads at its base portion and terminating in a re- 90duced portion, an elliptical frame adapted to be grasped in the hand and provided at one end with a screw threaded aperture adapted to engage the screw threads of said stem, an annular recess formed within the frame coaxial with the screw threaded aper- 95 ture and surrounding one end thereof, a concave seat formed in the body of said frame, and a flexible container fitted into said seat having a neck extending into said annular recess, whereby when the shank is 100 inserted into the aperture in the frame the reduced portion thereof will enter the neck of the flexible container to bind it against the wall of the recess.

In testimony whereof I affix my signature 105 in the presence of two witnesses.

THEODORE C. ADAMS.
